PNEUMATIC TIRE TREAD AND BUTTRESS COMBINATION

Robert F. Busch, St. Clair Shores, and William K. Pope,
Detroit, Mich., assignors to Uniroyal, Inc., New York,
N.Y.

Filed Sept. 9, 1969, Ser. No. 19,071

Term of patent 14 years

Int. Cl. D12—15

U.S. Cl. D90—20

Fig. 1.

FIG. 1 is a perspective view, partly schematic, of a pneumatic tire tread and buttress combination embodying our new design, it being understood that the pattern is repeated throughout the circumference of the tread and buttress, as shown schematically by solid lines. For convenience of illustration, applicants have omitted from FIG. 1 the representation appearing in FIG. 3 which extends axially inwardly from the lower external edges of the buttress.

FIG. 2 is an enlarged, fragmentary plan view of the tread and buttress of FIG. 1; and

FIG. 3 is a sectional view of the tread and buttress, taken substantially on the plane indicated by line 3—3 of FIG. 2.

We claim:

The ornamental design for a pneumatic tire tread and buttress combination, substantially as shown and described.
